APPARATUS FOR COMBINING AND EMPLACING CEMENTITIOUS SUBSTANCES

William Elmer Anderson, Kansas City, Mo., assignor to Jo Zach Miller III, Kansas City, Mo.

Application June 9, 1947, Serial No. 753,430

1 Claim. (Cl. 91—44)

1

This invention relates to the art of affixing cementitious substances to surfaces and the primary object is to provide a specially formed nozzle forming a part of the apparatus for producing and emplacing the cementitious substance.

The most important object of this invention is to provide a nozzle for apparatus of the aforementioned character, which nozzle is formed to present an intake port for air and water, the air serving not only to draw sand and cement into the nozzle but to atomize the water prior to entrance thereof into the nozzle for impinging upon and rendering such materials plastic and of proper consistency.

Another important object of this invention is the provision of a nozzle for said apparatus having a continuous bore therethrough, provided with a single inlet port circumscribing the bore for receiving both air for drawing the material into the nozzle and the atomized water, said water being introduced to the air at a point remote from the nozzle to the end that the mass of material is hydrated only with a pressurized spray of moisture and improper admixing is thereby avoided.

Another object of this invention is to provide a nozzle of the character above set forth having parts forming a portion of the bore thereof for receiving the hydrated mixture constructed to avoid "clogging" of the nozzle during use, through the medium of novel formation of said parts as well as the material from which said parts are made.

A further object of this invention is to provide a nozzle assembly having a cylindrical body provided with a tubular insert adjustably mounted to vary the extent of vacuum created in the body.

A still further object of this invention is the provision of a nozzle formed to direct the material tangentially thereinto and having a sliding tubular member movable to selected positions with respect to the incoming material whereby greater vacuum may be established as the weight and size of the particles of material is varied.

Other objects will be made clear or become apparent during the course of the following specification, reference being had to the accompanying drawings, wherein:

Fig. 1 is a schematic view of a portion of apparatus for emplacing cementitious substances having a nozzle therein that is made in accordance with the present invention.

Fig. 2 is a fragmentary enlarged longitudinal

2

condensed central sectional view through the nozzle of the apparatus.

Fig. 3 is a fragmentary longitudinal cross sectional view through a modified form of nozzle; and

Fig. 4 is a detailed sectional view through the main shut off valve shown in Fig. 3.

This application is related to Patents No. 2,231,489, dated February 11, 1941, No. 2,264,108, dated November 25, 1941, and No. 2,303,810, dated December 1, 1942.

The nozzle illustrated in Patent No. 2,231,489 has been found unsatisfactory in that compressed air is injected into the body portion thereof at a point spaced from the water inlet, resulting in the dry ingredients being forced into a stream of incoming water. The device shown in that patent when placed in use failed to provide adequate hydration since the water was not properly atomized within the nozzle, thus causing clogging due to unsaturated lumps forming therein. Further, clogging was found to be caused because of the provision of a second annular cavity presenting a space for collection of the cementitious material. And, finally the section of the nozzle receiving the substance as it passed outwardly as formed, became quickly damaged by the sand and gravel beyond use, necessitating frequent replacement.

The nozzle illustrated in Figs. 1 and 2 of the drawing accompanying this application has been found more satisfactory and comprises a pair of sections 10 and 12, the ends of which are in opposed, spaced apart relation and held in such position by a coupling 14. Coupling 14 bridges the space between the sections 10 and 12 and is provided with an annular cavity 16 formed in the inner face thereof which circumscribes the section 10. Sections 10 and 12 are tubular to present a continuous longitudinal bore through the nozzle.

Section 10 constitutes a pair of parts 18 and 20, said parts being threadably interconnected as at 22 and part 20 extending into one end of coupling 14 to terminate in spaced relation to the opposite end of coupling 14. A laterally extending external annular flange 24 integral with part 20 is disposed exteriorly of coupling 14 and joined to the proximal end of coupling 14 by a number of machine bolts or the like 26.

Part 18 is relatively short and receives one end of a flexible hose 28 leading to a material feeder 30. The outermost free end of part 18, which forms one end of the nozzle, has its innermost face beveled outwardly as the outermost end

thereof is approached as at 32 to the end that material entering the nozzle has no tendency to collect at this point and cause clogging of the nozzle.

The end of the part 20 of section 10 adjacent to the inner end of the section 12 is reduced to substantially a feather edge by tapering a portion of the length of said part 20 to produce a frusto-conical portion, the outer surface 34 of which cooperates with the inner surface of coupling 14 in directing compressed air and atomized liquid unto the section 12.

The coupling 14 is provided with an enlarged cavity 40 for receiving the section 12 and presenting an internal annular shoulder 42. Section 12 includes a metallic sleeve 44 encircling a flexible, tubular member 46 of rubber or the like. Member 46 extends outwardly beyond each end of the sleeve 44 and overlaps the outer surface of the innermost end of sleeve 44 to present a circumscribing portion 48. This overlapped portion 48 of member 46 is held in tight abutting relation with shoulder 42 by a lateral annular flange 50 integral with sleeve 44. This flange is secured to the proximal end of the coupling 14 by machine bolts or the like 52, and the inner face of sleeve 44 is beveled outwardly as at 54 adjacent the inner end thereof to the end that an enlarged inlet opening is presented in section 12 to receive material from section 10.

A tube 56 places annular cavity 16 in communication with a source of compressed air (not shown), such as a tank illustrated in the aforesaid patents. This tube includes a hollow nipple 58 and has a valve 60 interposed therein for controlling the passage of air to the nozzle.

A tube 62 having connection with a source of water (not shown) has a control valve 64 and a pipe 66 that connects with and extends into nipple 58 at a point remote from the nozzle and the cavity 16 thereof. That portion of pipe 66 within nipple 58 constitutes a coupling 68 for having an extension 70 of reduced diameter provided with an outlet port 72 disposed to direct water in the direction of flow of air currents in nipple 58 toward cavity 16 in the coupling 14.

It is easily understood from the foregoing that water or other liquid will enter nipple 58 from tube 62, through valve 64, coupling 68 and portion 70 thereof and be introduced into the stream of air in a fine jet. This liquid will be atomized as the same is forced into the cavity 16 and thence into section 12 where the same will admix with materials thereby effected without danger of clogging of the nozzle since the liquid never passes to the material in bulk and thereby causing the material to lump prior to passage from the nozzle.

It is notable further that at no point within the longitudinal bore through the nozzle is there restrictive surfaces tending to cause clogging. The member 46 will withstand many more hours of use before the sand and gravel of the mixture damage the same beyond efficient use. Removal of bolts 52 provides quick and easy replacement of member 46 when such becomes necessary.

The amount of air and water, and thus the amount of material drawn into the nozzle may be selected through the provision of a number of metallic rings 74 interposed between flange 24 of part 20 and the proximal end of coupling 14. The number of these rings 74 utilized determines the size of the passage 38 between surfaces 34 and 36 of part 20 and coupling 14 respectively.

The nozzle shown in Figs. 3 and 4 includes a body 100 of cylindrical form and made from a

single piece of material to present a longitudinal bore 102 rather than sectional as in the form shown in Figs. 1 and 2.

A hose 104 comparable to hose 28 shown in Fig. 1 directs the material into the body 100 through connection with a coupling 106. This coupling 106 connects with an inlet opening 108 formed in body 100 intermediate the ends thereof and is disposed at an angle with the body 100. Thus, instead of projecting the material coaxially into the body 100 as is true with the connector 18, this coupling 106 causes the material to flow into body 100 tangentially to its longitudinal axis.

A hose 110 comparable to hose 56 and a hose 112 which is like hose 62 of Fig. 1, directs compressed air and water respectively into body 100. Air and water pass through a main control valve 114, while the air is separately controlled by a conventional shut-off valve 116 interposed between hose 112 and valve 114.

Fig. 4 illustrates the form of valve 114. A core 118 is rotatably mounted within the housing of valve 114 and actuated manually by a handle 120. This core 118 has an opening 122 therethrough for permitting passage of air from hose 110 to body 100 when core 118 is turned to the position shown in Fig. 4. Core 118 is also provided with a port 124 communicating at one end with the opening 118 and at its opposite end with a nipple 126 when core 118 is disposed as shown in Fig. 4. The nipple 126 is threaded into the housing of valve 114 and receives valve 116 at its outermost end.

It is clear that turning of core 118 by manipulating handle 120 will prevent passage of air or water into body 100 even if valve 116 remains open. Thus only one action on the part of the operator in controlling the operation of the nozzle and valve 116 may be set to permit passage of a selected amount of water without readjustment during each shut-off operation.

The predetermined admixture of air and water is directed into one end of the body 100 by a plug 128 interposed between valve 114 and body 100. This mixture then passes through a tubular member 130 slidably mounted in body 100. The member 130 has an outside diameter at one end thereof adjacent to the plug 128 substantially the same as the diameter of bore 102. A set screw 132 releasably holds member 130 in any selected position within body 100 with respect to material inlet opening 108.

The outlet end of body 100 opposite to plug 128 is externally threaded to receive a relatively short steel pipe section 134 for use in sandblasting. The length of pipe 134 will govern the extent of spray of material passing from the nozzle. In the event lighter material is to be emplaced, i. e. when the nozzle is to be used for the same purpose as the nozzle shown in Fig. 2, then a short hose of rubber or other flexible material is slipped over the outlet end of body 100.

The slidable, tubular member 130 is shown in Fig. 3 positioned to create a maximum amount of vacuum within body 100. As member 130 is moved toward the plug 128, the extent of vacuum in body 100 is decreased and the nozzle is then adaptable for use with lighter material passing through hose 104.

The use of the nozzle shown in Fig. 3 has the advantage over that shown in Fig. 2 of being adaptable to handle heavy material used particularly in sandblasting. The pressure necessary to draw such heavy material into the nozzle is made

possible by use of this modified form whereas the nozzle of Fig. 2 is not so adaptable.

Having thus described the invention, what is claimed as new and desired to be secured by Letters Patent is:

In a nozzle, a tubular body adapted for passage of material therethrough and having an annular inturned flange formed therein; an elongated sleeve; a rubber tube extending through the sleeve, said tube being rebent upon itself at 10 one end thereof in partial overlapping relationship to the outermost face of the sleeve at the proximal end of the latter; and means for holding a portion of the sleeve and the tube within the body with said rebent end of the tube bearing against said flange. 15
